WARP CONDITIONING PROCESS FOR TYING-IN MACHINES Stoney Drake, Norfolk, Va., assignor to
Drake Corporation, Norfolk, Va.No Drawing. Application October 29, 1954,
Serial No. 465,741

9 Claims. (Cl. 28—72.6)

This invention relates to a process of warp conditioning and more particularly, for conditioning the leading and trailing ends of warp sheets. It relates particularly to a method of conditioning the leading and trailing ends of warp sheets of high-twist yarns, preferably synthetic yarns, to prevent snarling, twisting or otherwise fouling up the 25 yarns in the steps of attaching the yarns to a warp beam or in threading them through the drop wires, heddles and reeds of a loom. While this method is particularly adapted to the treatment of high twist synthetic or artificial yarns, it is applicable to any yarns having twist sufficiently high to cause twisting, or snarling thereof when being handled.

Before a warp sheet can be used on a loom for weaving, the individual threads thereof must be threaded through the drop wires of the warp stop motion, then through the heddles of the loom harness and finally through the reeds of the loom before being attached to the warp beam. In performing this threading operation, the individual threads must be manipulated manually or by means of a machine such as the well-known "Barber-Colman" type tying-in machine. When these threads are of the high-twist type, and particularly when S-twist threads are doubled with Z-twist threads to form a two-ply warp yarn, there is a tendency for the threads to kink or snarl and to twist about one another, forming a sort of rope-like mass. It therefore becomes difficult, if not impossible, to handle the processing in a satisfactory manner.

When the warp on a loom beam is about exhausted (and it is necessary to replenish it), it is desirable to attach the individual threads of the new warp respectively to those of the loom beam, to avoid the necessity of going through the threading up steps. To do so, the warp beam of the loom, if it is not completely loaded, with the trailing ends of the old warp, together with the drop wires, heddles and reed, is brought to the tying-in stand. Here the new warp on its loom beam is placed in juxtaposition to the old warp and the individual threads or ends of the new warp are respectively tied to those of the old warp. This may be done manually, but is commonly done with tying-in machines, one example of which is the well-known "Barber-Colman Tying-In Machine." It is in this operation that the inherent snarling, kinking, or twisting of the high-twist warp ends is particularly objectionable.

In textile mill operation, the spun single threads and/or ply threads are formed into a warp sheet and are wound onto a loom beam by means of a machine known as a "slasher." A suitable number of spools or section beams of warp threads to make the desired warp sheet are placed at the rear of the "slasher." The threads are led from such supplies in sheet form through a size box where they are properly sized or coated with starch or other suitable sizing agent to give them sufficient strength to withstand the handling and to resist abrasion in the operation of being woven. The wet sized sheet of warped threads is then passed about one or more heated drum dryers to evaporate excess moisture. The warp sheet is next divided or leased by passing alternating groups of threads on either side of

one or more lease rods. This divided condition is usually maintained by placing lease cords in the leading and trailing ends of the warp sheet in the positions occupied by the lease rods. From the lease rod, the warp threads are individually passed through the dents of a separator comb or an expansion comb. The leasing and separating steps are for the purpose of preventing the yarns from sticking together when wound onto the loom beam to which they are led from the comb. Most warp threads, unless they 10 contain high twist yarns, remain inert and free of kinking and snarling in the warp sheet.

However, when the warp contains or is composed of high-twist yarns, but especially when ply yarns composed of S-twist singles, plied with Z-twist singles are used, the 15 troubles above noted are encountered. This invention is aimed at preventing these troubles.

It is, therefore, an object of this invention to treat the leading and trailing ends of a warp sheet to prevent snarling, kinking or intertwisting of the warp threads during 20 handling.

Another object of the invention is to treat portions of the warp, while on the slasher, to prevent kinking or snarling of the end thereof during handling.

A further object of this invention is the application, to 25 a portion only of the warp of a twist-setting medium while such warp is on the slasher.

An additional object of this invention is the application of a twist-setting medium to the end portions only of a warp sheet.

Other objects will appear during the course of the following specification.

After threading a warp containing threads which are likely to kink or snarl, onto a slasher and prior to starting the run of a new beam, a portion for a few yards, say three or four yards, near the leading end, should be treated to prevent the inherent kinking, snarling or twisting. This should be done as the machine is started and before it comes up to full speed. This is accomplished by spraying on the warp sheet, from above, a mist of a suitable twist-setting agent. This may be done by the use of any suitable atomizing sprayer. If it is to be done only occasionally, one may use a hand sprayer of the garden or "Flit" gun type which produces a fog or mist of the liquid.

The run of the slasher is continued until nearly enough 45 yarn is wound on the loom beam. Just prior to stopping the machine, it operates at low speed. During operation of the slasher, there are always six or eight yards of yarn between the separator, expansion comb and the dryer drums. As the slasher slows down and is about to stop 50 for doffing the loom beam, the yarns between the comb and the dryer are sprayed, from above, with a mist or fog of twist-setting liquid. This mist settles onto the warp and coats the yarns sufficiently with little likelihood that they will become saturated with excess conditioning medium. There is thus formed a band, across the warp sheet and about six or eight yards long, wherein the yarns 55 are twist-set to prevent snarling or kinking in handling.

The use of a hand sprayer to atomize the liquid, as above noted, may suffice for occasional use. However, 60 in mills where most of the warp used is of the high-twist type or of the type wherein S-twist singles are doubled or plied with Z-twist singles, it may be expedient to equip the slasher with spray heads. Devices such as atomizer-type humidifier heads may be mounted on the machine to be positioned above the warp in the region between the dryer drum and the slasher where the threads are separated by the lease rods and the comb. These spray heads 65 may be supplied with twist-setting liquid under pressure from a suitable container. When in use, they will form a fog or mist above the warp which will operate as above noted for the hand sprayer method.

As noted above, about six or eight yards of warp are

treated. After the machine is stopped, the usual slasher tapes are applied at about the middle of the band of conditioned warp. The sheet of warp is now severed between a pair of slasher tapes and one conditioned portion becomes the trailing end of the warp wound on the loom beam about to be doffed. The other end will become the leading end of a warp about to be wound on a new loom beam.

Thus, there is provided a warp, composed of high-twist yarns having an inherent tendency to twist or snarl, which is amenable to use in tying-in machine or in threading into loom harness, drop wires and reeds in a substantially inert condition without any annoying tendency to snarl, kink, intertwist or form objectionable ropes.

The products most desirable for this use should contain a water-soluble lubricant of oily nature or an emulsion of a lubricant, a suitable penetrating agent, a hygroscopic agent, and a fungicide. Solutions which have been found satisfactory contain oily materials such as soap, sulfonated castor oil, sulfonated olive oil and other sulfonated vegetable or animal oils with which may also be included some non-sulfonated animal, vegetable and/or mineral oils, such as neat's-foot oil, soya bean oil, white mineral oil, etc. These oils or oily materials and soaps are all included by the expression "oily derivative material." These materials may also be included by the expressions, "emulsifying agents, homogenizing agents, or sulfonated high-molecular weight, aliphatic materials."

To cause quick penetration, it is desirable to use hygroscopic materials, such as glycerine, glycol, and ethanol amines.

As a fungicide, it is satisfactory to use phenol, cresol, naphthols, chlorinated and/or nitrated phenolic compounds, pine oil, formaldehyde, fluorides, etc.

The ingredients of the solution should be of such nature as not to cause sticking or gumming of the machine parts.

It should also be apparent from the foregoing description that the loom beam with the warp yarns wound thereon and treated as above described, constitutes a novel article of manufacture.

Although a specific example of the process only has been given, it is to be understood that the process is not to be limited except within the scope of the appended claims.

What I claim is:

1. A method of warp preparation for high-twist warp yarns which comprises applying a twist-setting liquid to only a portion of each end of a sized and dried warp sheet during slashing as it is being prepared for weaving, to prevent kinking and snarling of the ends of the warp yarns

during threading up of a loom and during tying-in of a new warp.

2. The process of claim 1 in which the twist-setting liquid is sprayed in atomized form above the warp threads just prior to the completion of a warp.

3. In a method of warp preparation for high twist yarns which includes sizing and drying a warp sheet of such yarns, separating and leasing the warp yarns and winding the sized yarns onto a loom beam; the improvement which 10 comprises, just prior to the completion of a beam, applying to a portion of the yarns which constitute the trailing end of the yarns on one beam and the leading end of the yarns on another beam, a twist setting composition in mist form.

4. The method of claim 3 in which the twist-setting liquid comprises a water solution of an oily material and contains a penetrating agent, and a fungicide.

5. As a new article of manufacture, a sheet of sized warp yarns having an inherent tendency to kink and snarl, wound on a loom beam in which a portion of such warp 20 at the leading and trailing ends only of the warp are twist-set to prevent kinking during threading up a loom and during tying-in a new warp.

6. As a new article of manufacture, a sheet of sized warp yarns having inherent tendency to kink and snarl having the ends only of the individual yarns twist-set for a distance of from three to four yards to prevent kinking and snarling during threading up and tying-in operations.

7. The method of twist-setting the end portions only of a warp of yarns, having an inherent tendency to kink and snarl, which comprises, while the yarns are on a slasher, after the sizing and drying of said yarns and immediately prior to the doffing of a wound mass thereof, applying to said warp yarns from above a mist of a twist-setting liquid.

8. A method of warp preparation for high-twist warp 30 yarns which comprise applying a twist-setting material to a portion of each end of a sized and dried warp sheet, as it is being prepared for weaving, to retard the snarling tendency of the high-twist yarns during threading-up of a loom and during tying-in of a new warp.

9. A method of warp preparation for high twist yarns on a slasher having customary sizing, drying and leasing means, the steps comprising just prior to a doffing operation, spraying onto the sized and dried warp sheet a twist setting liquid in mist form, applying at least a pair of 40 slasher tapes at about the middle of the treated area and severing the so treated warp between the tapes.
